ELECTRON DISCHARGE DEVICE EMPLOYING
CAVITY RESONATORSJohn Truell, Princeton, N. J., assignor to Radio
Corporation of America, a corporation of Dela-
ware

Application July 22, 1944, Serial No. 546,175

7 Claims. (Cl. 315—5)

1

My invention relates to electron discharge devices and associated circuits, more particularly to such devices utilizing cavity resonators and useful at ultra high frequencies.

One type of electron discharge device of this kind is known as a reflex oscillator. The present types of reflex oscillators are useful as local oscillators but are not particularly suitable for use as power tubes which can be utilized for pulse operation. In the conventional type reflex oscillator employing cavity resonators, a beam of electrons is directed through a cavity resonator of the type formed by a surface of revolution about an axis, the beam being directed along this axis through an aperture and past a gap in the resonator wall around the beam path and toward a reflecting electrode. As the frequency of intended operation is increased, the size of the resonator and the size of the aperture at the gap becomes smaller and smaller, limiting the beam current that can be put through the aperture at the gap at a given voltage. For frequencies as high as 3×10^{10} cycles/sec., the size of the aperture mentioned becomes quite small, about 0.4 mm. in diameter. As a result the useful beam current is seriously limited. While the cavity resonator must be kept small for high frequencies, it is not the size of the cavity resonator which at present is a limiting factor, except that it requires a small aperture because the gap is necessarily small.

It is, therefore, an object of my invention to provide an improved electron discharge device and associated circuit of the cavity resonator type and useful at ultra high frequencies.

A further object of my invention is to provide such a device utilizing a cavity resonator and useful as a reflex oscillator of the velocity modulation type.

A still further object of my invention is to provide such a reflex oscillator having comparatively high power outputs although employing a cavity resonator of small size.

A more specific object of my invention is to provide a reflex oscillator utilizing a cavity resonator and having high beam current densities and large currents.

The novel features which I believe to be characteristic of my invention are set forth with particularity in the appended claims, but the invention itself will best be understood by reference to the following description taken in connection with the accompanying drawing in which Figure 1 is a longitudinal section of an electron discharge device and associated circuit made ac-

2

cording to my invention, Figure 2 is a section taken along the line 2—2 of Figure 1, Figure 3 is a schematic diagram showing the electron discharge device and associated circuit shown in Figures 1 and 2 and the associated voltage sources.

Briefly, in accordance with my invention I provide an electron discharge device having an annular cathode for directing electrons radially toward a central electrode used as a reflector. Positioned between the reflector and cathode is a cavity resonator of special construction, which while provided with a small size gap has nevertheless a comparatively large aperture permitting a large beam current of high density to be directed therethrough.

Referring specifically to Figures 1 and 2, an electron discharge device made according to my invention includes an evacuated envelope 10 provided with the usual press 11 through which the 20 various electrode lead and support wires extend for supporting the electrode mount and associated resonator within the envelope.

An annular indirectly-heated cathode 12 is coated on its inner surface with the usual carbonates to deliver a disc-like beam of electrons directly radially toward the axis of the cathode. The cathode is heated by means of the heater 13. A reflecting electrode 14 is positioned along the axis of rotation of the cathode structure for reflecting electrons back toward the cathode. On opposite sides of the cathode is positioned a pair of ring-like electrode members 15 and 16 electrically connected to the cathode by means of the straps 17 and 18 for maintaining these ring electrodes at cathode potential for forming the disc-like beam of electrons directed toward the axis of the electrode structure. Following these beam-forming ring-like electrodes is a pair of electrodes 19—20 maintained for operation of the device at a negative potential for focusing electrons through the aperture of the cavity resonator to be described. These ring-like elements are electrically connected together by means of lead wire 21.

Positioned between these focusing electrode elements 19—20 and the reflecting electrode 14 is the cavity resonator which comprises a pair of comparatively thick ring-like elements 22 and 23 electrically connected together through conductor 24 by means of straps 25—26 and having cavities 28 and 28'. Each of these ring-like elements is closed on the inner side by means of ring-like elements 29, thus providing a resonant space having a gap adjacent the path of the electrons. 55 Thus there is provided an annular cavity resona-

tor having a small width gap adjacent the beam path but having a large aperture for permitting a large beam current to flow through the resonator.

Between the resonator and the reflector is a second electrode which acts as a focusing electrode and comprising two ring-like elements 30—31 electrically connected together by means of the conductor 32. All of these electrode elements and circuit elements are maintained in fixed spaced position by means of the glass bead support construction indicated at 33, 34, 35 and 36. There may be several groups of these, preferably three groups. The reflecting electrode 14 may be provided with lead 37 and the cathode heater with leads 38 and 39 for supplying heater current to the cathode heater 13, which is insulated from the cathode by means of an insulating coating.

It will thus be apparent that a large beam current can be directed toward the reflecting electrode 14. The cathode has a very large emitting area and due to the fact that the transverse cross section of the beam becomes less as the reflecting electrode is approached, the current density increases, thus resulting in two factors which increase the power output of the tube, that is a large current of high current density.

The output may be taken from the cavity resonator by means of the coaxial line or wave guide 40—41 having a loop 44 at the cavity end. This line passes through support 42 sealed to the envelope, the coaxial line being hermetically sealed in the support at 43.

As best shown in Figure 3, the cathode heater 13 is supplied from the voltage source at 50 and the voltage source for the various other electrodes is indicated at 51. It will be observed that the resonator 22—23 is maintained at the highest positive potential while the reflector 14 is maintained at negative potential less than the cathode 12, the electrode 19 being maintained at a more negative potential for properly focusing the beam. The voltage between the cathode and the cavity resonator may be of the order of 1500 to 2000 volts.

In the operation of the device, electrons from the cathode 12 are focused by the ring electrodes 19—20 through the resonator gap where they are velocity modulated in conventional manner by the oscillatory field in the resonator. After passing through the resonator gap, the electrons approach the negative reflecting electrode 14 and are reflected thereby back through the resonator, being focused by the ring electrodes 19—20 as they pass therethrough. During their transit from the resonator toward the reflecting electrode and back, the electrons form bunches which, in passing back through the resonator, drive the resonator at its resonant frequency to render the device self-oscillatory.

While I have indicated the preferred embodiments of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

What I claim as new is:

1. An electron discharge device having means including a cathode having a curved emitting sur-

face for supplying and directing a stream of electrons converging toward the axis of curvature of said surface, an electrode positioned at said axis, a curved cavity resonator positioned between said cathode and said electrode and having a gap therethrough of relatively-small beam area compared to the area of said emitting surface in the path of said converging beam, and focusing electrodes spaced from said cathode, electrode and resonator and positioned between the cathode and cavity resonator and between the cavity resonator and the electrode at said axis, each of said focusing electrodes comprising a pair of axially-spaced curved elements providing a gap between the adjacent edges thereof through which the path of said converging beam lies, whereby the electron density in the beam will be substantially greater in said gap than adjacent said cathode.

2. An electron discharge device having a cathode for supplying a stream of electrons, an electrode toward which said electrons are directed, and a cavity resonator positioned between said cathode and said electrode and including a solid conducting element having a recess formed in one surface thereof and adjacent the beam path, and a conducting member extending transversely of the beam path and positioned on said conducting element and extending over the recess and forming therewith a cavity resonator, the edges of said element and said member adjacent the beam path forming a gap past which said electrons are directed during operation of said device.

3. An electron discharge device having means including a cathode of annular shape for directing a stream of electrons radially inwardly toward the axis of said cathode, a first electrode positioned at the axis of said cathode, an annular cavity resonator positioned between said cathode and said electrode and having a gap in the path of said electron stream, and a focusing electrode comprising a pair of axially-spaced annular elements positioned between and spaced from the cathode and cavity resonator and providing a gap between the adjacent edges of said annular elements through which the path of the stream of electrons lies.

4. An electron discharge device having means including a cathode of annular shape for directing a stream of electrons radially toward the axis of said cathode, an electrode positioned at the axis of said cathode, an annularly-shaped cavity resonator positioned between said cathode and said electrode and having a gap in the path of said electron stream, and electrodes of annular shape positioned between the cathode and cavity resonator and between the cavity resonator and the electrode positioned at said axis, each of the annularly shaped electrodes comprising a pair of axially spaced ring members providing a gap between the adjacent edges of said ring members, the path of the stream of electrons passing through each gap.

5. An electron discharge device having means including a cathode of annular shape for directing a stream of electrons radially toward the axis of said cathode, an electrode positioned at the axis of said cathode, and an annularly shaped cavity resonator positioned between said cathode and said electrode, and electrodes of annular shape positioned between the cathode and cavity resonator and between the cavity resonator and the electrode positioned at said axis, each electrode of annular shape comprising a pair of axially spaced ring-members pro-

viding a gap between the adjacent edges thereof, the path of the stream of electrons passing through each gap, said cavity resonator comprising a pair of axially spaced comparatively thick ring-like members each having an annular recess adjacent the path of the stream of electrons and a ring-like element extending over each recess to form therewith a cavity resonator, the edge of said thick ring-like member and the edge of the ring-like element extending over said recess providing a gap past which electrons are directed toward the electrode at said axis.

6. An electron discharge device having means including a cathode of annular shape for directing a stream of electrons radially toward the axis of said cathode, an electrode positioned at the axis of said cathode, and an annularly shaped cavity resonator positioned between said cathode and said electrode, said cavity resonator comprising a pair of comparatively thick ring-like members spaced axially and each having an annular recess adjacent the path of the stream of electrons and a ring-like element extending over each recess to form therewith a cavity resonator, the edge of said thick ring-like member and edge of the ring-like element providing a gap past which electrons are directed toward the electrode at said axis.

7. An electron discharge device having means

including a cathode of annular shape for directing a stream of electrons radially toward the axis of said cathode, an electrode positioned at the axis of said cathode, and an annularly shaped cavity resonator positioned between said cathode and said electrode, said cavity resonator including a comparatively thick ring-like member having a recess in the inner wall adjacent one edge of said ring-like member, a ring-like element on the inner surface of said ring-like member and extending over said recess, the edge of said thick ring-like member and edge of said element providing a gap past which electrons are directed toward the electrode.
